UNITED STATES PATENT OFFICE.

ALAN D. DAUCH, OF PITTSBURGH, PENNSYLVANIA, ASSIGNOR TO GEORGE J. HAGAN COMPANY, OF PITTSBURGH, PENNSYLVANIA, A CORPORATION OF PENNSYLVANIA.

ENAMELING FURNACE.

Application filed August 27, 1923. Serial No. 659,443.

To all whom it may concern:

Be it known that I, ALAN D. DAUCH, residing at Pittsburgh, in the county of Allegheny and State of Pennsylvania, a citizen 5 of the United States, have invented or discovered certain new and useful Improvements in Enameling Furnaces, of which improvements the following is specification.

The invention described herein relates to 10 certain improvements in furnaces for burning enamel on the surfaces of metal articles and has for its object a construction of supporting racks permitting of their easy and quick renewal, and a construction of rack 15 support permitting of a rapid heating of the articles. It is a further object of the invention to provide for the simultaneous discharging and charging of the furnace. The invention is hereinafter more fully de- 20 scribed and claimed.

In the accompanying drawings forming a part of this specification Fig. 1 is a sectional elevation of a furnace embodying the improvements claimed herein; Fig. 2 is a 25 section plan view, the plane of section being indicated by the line II--II, Fig. 1; Fig. 3 is a transverse section on a plane indicated by the line III--III Fig. 4; Fig. 4 is a detail view showing in elevation a 30 section of a longitudinal beam and a rack mounted thereon; Fig. 5 is a top plan view of the rack supporting beam; Fig. 6 is a similar view of a section of the rack; and Fig. 7 is a transverse section on a plane in- 35 dicated by the line VII--VII, Fig. 4. Fig. 8 is a sectional elevation of an enameling furnace and mechanism for charging and moving articles into and from such furnace; and Fig. 9 is a top plan view on an enlarged 40 scale of the charging mechanism.

In the practice of the invention the furnace is preferably provided with charging and discharging openings at its ends and as it is preferred that heat should be applied directly to upper and under surfaces of the articles, the furnace is made of suitable height, and the articles supported as hereinafter described, approximately midway of the interior height of the furnace. 45 Horizontal members, or beams, 2, preferably formed of refractory material, are arranged across the furnace and supported at their ends by the side walls of the furnace, and also by preference at intermediate points by piers 3. These transverse 55

members or beams 2 are spaced distances apart and from the ends of the furnace dependent on the lengths of the sections 4 of the rack supports preferably formed of a refractory alloy. These sections are 60 anchored at one end of the transverse beams by pins 5 projecting into the latter, and in order to maintain the sections in alinement, adjacent ends are interlocked in any suitable manner. In the construction shown, 65 one end of each section is provided with jaws 6 for the reception of the plain end of the next adjacent section. As it is desirable to employ a large number of these longitudinally arranged sections and at the same time to provide spaces between adjacent lines of sections to permit of the upward passage of heat between them, the sections are made comparatively thin and provide lateral projections at their lower edges and 70 adjacent to the ends of the sections, adapted to bear on the upper surfaces of the beams. At one end these lateral projections are formed by the jaws 6 and at the opposite end by ears 7. By reference to Figs. 1, 2 and 5, it will be seen that the sections are 75 made by such lengths and so supported that adjacent ends will not abut, thus permitting of expansion of the sections.

As shown in Figs. 1 and 4, the racks are 80 formed of bars 9 provided on one side with a plurality of pointed pins 10. The bars which are arranged on the supporting sections are preferably a little shorter than the sections. Any suitable means may be em- 85 ployed for holding the bars on the sections in such manner as to permit of their easy replacement by other bars. A desirable construction to this end consists in forming flanges 4^a along the upper edges of the sections 4 and cutting notches in the flanges for the reception of lugs 11 so formed on the bars 9 that a portion of the lugs will project down on one side of the sections, while the others will project down the other side of 90 the sections.

For charging articles into and removing the article from the furnace, two substantially similar mechanisms are employed, ar- 105 ranged respectively at opposite ends of the furnace as shown in Fig. 8. Each of said mechanisms consists of a fork having a plurality of prongs or fingers 12 spaced such distances apart that when a fork is pushed into the furnace the fingers will be 110

- in line with spaces between the rows of pins of the rack in the furnace. The fingers are made of lengths substantially equal to the length of the furnace and are so supported that they may be moved into and out of the furnace and also raised and lowered. In the construction shown herein for imparting the desired movements to the fork, the prongs 12 are secured at their inner ends to a frame consisting of vertical bars 13 and brackets 14 secured to the bars which have their respective ends pivotally connected to a pair of levers 15 and 16 fulcrumed at 17 on the posts or standards 18 secured to the frame of the machine. The forks are supported in horizontal normal position by abutments 19 secured to the vertical bars 13. The upper ends of the vertical bars 13 are adjustably connected to the upper levers by turn buckles 20. By adjusting the turn-buckles the normal position of the fork can be varied. A counterbalancing weight 21 is secured to the rear ends of the levers. The members of the pairs of levers are connected by cross bars 22 and these cross bars are connected to the inner end of an operating lever 23, which is preferably provided with a locking device adapted to engage teeth on a sector 24, whereby the fork may be held in proper position while being moved into and out of the furnace. The charging mechanism is mounted on wheels 25 movable along rails 26 in alinement with the furnace. The back and forth movement of the mechanism is preferably effected by means of a hand operated wheel 27 on a shaft carrying a sprocket wheel 28 which is operatively connected by a chain 29 to a sprocket wheel on one of the wheels 25.
- In operating the furnace the articles to be treated are arranged on the fork of one of the charging mechanisms which is then moved towards the furnace, the fork having been raised to such a position as to pass above the pins 10 in the furnace. The forks are next lowered, the prongs passing between the rows of pins 10, thereby transferring the articles to the pins. The fork is then withdrawn and another charge of material placed thereon. As soon as the articles have been properly heated the fork at the other end is run into the furnace, the prongs passing below the articles resting on the pins. The fork is then raised to lift the articles away from the pins and the fork withdrawn. It will be seen that the operation above described is similar to the operation of what is termed a continuous heating furnace, the articles being moved at all times in the same direction.
- I claim herein as my invention:
1. An enameling furnace having in combination therewith a plurality of beams or members arranged in spaced relation within the furnace and racks consisting of a plurality of longitudinal sections provided with pins for supporting articles and detachably supported by said beams or members.
  2. An enameling furnace having in combination therewith a plurality of beams or members arranged in spaced relation within the furnace, rack supports arranged in spaced relation on the beams or members and consisting of a plurality of longitudinal sections and racks provided with pins for supporting articles to be treated detachably supported by the rack supports.
  3. An enameling furnace having in combination therewith a plurality of spaced beams or members arranged intermediate the height of the heating chamber, racks provided with pins for supporting articles to be treated arranged in spaced relation on said beams and means whereby heat is applied to the upper and undersides of articles supported by the racks.
  4. An enameling furnace having in combination therewith a plurality of spaced beams or members arranged transversely of and in a plane intermediate the height of the chamber of the furnace, rack supports arranged longitudinally of the chamber and consisting of a plurality of longitudinal sections and racks provided with pins for supporting the articles to be treated detachably secured to the rack supports and means for applying heat to the upper and underside of articles supported by the racks.
  5. An enameling furnace having in combination therewith a plurality of spaced beams or members arranged transversely of and in a plane intermediate the height of the chamber on the furnace, rack supports arranged longitudinally of the chamber and consisting of a plurality of longitudinal sections, and racks consisting of a plurality of longitudinal sections and detachably secured to the rack supports.
  6. An enameling furnace having in combination therewith rack supports extending longitudinally of the furnace and racks provided with pins consisting of a plurality of sections and detachably secured to the rack supports.
  7. An enameling furnace having in combination therewith beams or members arranged transversely of the furnace and in spaced relation one to the other, rack-supports consisting of a plurality of sections extending longitudinally of the furnace and supported by said beams, each section being provided with means for detachably anchoring such section to a transverse beam, the ends of such sections being adapted to interlock so as to maintain the sections in alinement, a rack provided with pins detachably secured to such supports.
  8. An enameling furnace having in combination therewith beams or members arranged transversely of the furnace and in

- spaced relation one to the other, rack-supports consisting of a plurality of sections extending longitudinally of the furnace and supported by said beams, each section being
- 5 provided with means for detachably anchoring such section to a transverse beam, the ends of such sections being adapted to interlock so as to maintain the sections in alignment, and racks consisting of a plurality of
- 10 sections, each provided with pins and with means for detachably engaging the rack supporting sections.
9. An enameling furnace having in combination therewith a plurality of spaced beams or members arranged intermediate the height of the chamber, members carrying a plurality of pins supported by the beams arranged in spaced relation on the beams and means whereby heat is applied to
- 15 20 the upper and under sides of articles supported by the pins.
10. An enameling furnace having in combination therewith a plurality of spaced beams or members arranged transversely of the furnace and supported by said beams, each section being provided with means for detachably anchoring such section to a transverse beam, the ends of the sections being provided with interlocking elements adapted to permit of the independent expansion and contraction of the sections.
- 25

the chamber in the furnace, supporting members consisting of a plurality of sections arranged longitudinally of the furnace, a plurality of pins supporting the articles to be treated carried by the respective sections and means for applying heat to the upper and under sides of articles supported by the pins.

11. An enameling furnace having in combination therewith beams or members arranged transversely of the furnace and in spaced relation one to the other, supporting members consisting of a plurality of sections extending longitudinally of the furnace and supported by said beams, each section being provided with means for detachably anchoring such section to a transverse beam, the ends of the sections being provided with interlocking elements adapted to permit of the independent expansion and contraction of the sections.

In testimony whereof, I have hereunto set my hand.

ALAN D. DAUCH.
